UNITED STATES PATENT OFFICE.

FREDERICK R. HUSE, OF BOSTON, MASSACHUSETTS.

SHADE-HOLDER.

SPECIFICATION forming part of Letters Patent No. 772,886, dated October 18, 1904.

Application filed March 5, 1904. Serial No. 196,685. (No model.)

To all whom it may concern:

Be it known that I, FREDERICK R. HUSE, of Boston, county of Suffolk, State of Massachusetts, have invented an Improvement in Shade-Holders, of which the following description, in connection with the accompanying drawings, is a specification, like characters on the drawings representing like parts.

This invention relates to shade-holders for Welsbach and other incandescent lamps, and has for its object to construct an improved form of shade-holder and also to provide a mica chimney, which is ordinarily used on Welsbach burners, with a shade-holder adapted to be removably connected therewith.

Figure 1 shows in side elevation and partial section a mica chimney provided with a shade-holder embodying this invention. Figs. 2 and 3 are enlarged details showing side and plan views of one of the brackets of the shade-holder. Fig. 4 is a modified form of bracket which may be employed.

The mica chimney is composed, essentially, of several sections *a* of mica secured together by longitudinal strips *b* of metal and by metallic end rings *c*. The shade-holder consists of several brackets *d*, adapted to be secured to the longitudinal strips *b*, and, as represented in Figs. 1, 2, and 3, the brackets are made of wire, yet they may be made of sheet metal, as shown in Fig. 4, and in either instance they are formed or provided with an inclined side or edge upon which the shade rests and with a pair of hooks *d'*, which are disposed in vertical alinement. The hooks are projected through holes *d''*, provided in the longitudinal metal strips *b* of the chimney, and thereby brought into firm engagement with said chimney. The chimney will be provided with a plurality of brackets arranged in the same plane to constitute the shade-holder.

The brackets *d* may be removed from the chimney at will, so that in case it is not desired to use them the chimney will be devoid of objectionable projections or extensions, although the longitudinal metal strips *b* of the chimney may be provided with holes *d''*, so that whenever desired the brackets may be engaged therewith.

The strips *b* may each have several holes *d''*, 50 if desired, arranged in a vertical row, so that the shade-holder may be disposed at different elevations.

Having thus described my invention, what I claim as new, and desire to secure by Letters Patent, is—

1. A lamp-chimney having holes therethrough, and a shade-holder comprising brackets having upper and lower hooks in vertical alinement, said hooks passing through the holes in the lamp-chimney, substantially as described.

2. As an article of manufacture, a lamp-chimney composed of sections of mica having holes therethrough and secured together by longitudinal strips having holes in alinement with the holes in the mica sections, and a shade-holder consisting of brackets having hooks in vertical alinement which pass through the holes in the longitudinal strips, and pass 70 through the holes in the mica sections and bear against the same, substantially as described.

3. As an article of manufacture, a lamp-chimney provided with holes therethrough, 75 and a shade-holder comprising brackets provided with downwardly-extending hooks in vertical alinement, said hooks designed to engage the holes of the lamp-chimney, substantially as described.

4. As an article of manufacture, a lamp-chimney provided with holes, a longitudinal strip provided with holes, and a shade-holder comprising brackets having upper and lower hooks, said lower hook being longer than the upper one, and both of said hooks designed to pass through the holes in the lamp-chimney and the holes in the longitudinal strips, substantially as described.

In testimony whereof I have signed my name 90 to this specification in the presence of two subscribing witnesses.

FREDERICK R. HUSE.
